United States Patent Office

Des. 185,743
Patented July 28, 1959

185,743

TERMINAL CONNECTOR LUG

John J. Edwards, Roselle, N.J., assignor to The Thomas & Betts Co., Elizabeth, N.J., a corporation of New Jersey

Application April 30, 1958, Serial No. 50,671

Term of patent 14 years

(Cl. D26—1)

Fig. 1.

Fig. 2.

Fig. 2a.

Fig. 2b.

Fig. 3.

Fig. 1 is a top plan view of a terminal connector lug, showing my new design,

Fig. 2 is an end elevational view,

Fig. 2a is a side elevational view, the opposite side being substantially a mirror image thereof,

Fig. 2b is an opposite end elevational view thereof,

Fig. 3 is a longitudinal vertical cross-sectional view taken through the center of the lug in Fig. 2, and stippled to indicate contrast in appearance.

I claim:

The ornamental design for a terminal connector lug, as shown and described.
